BUCKET TOOTH UNIT

Marshall J. White, Marysville, Calif.

Application April 7, 1943, Serial No. 482,112

8 Claims. (Cl. 37—142)

This invention relates generally to an improved bucket tooth unit for excavating buckets as used on power shovels, dredges and like equipment; the bucket tooth unit being of the type which includes a rearwardly opening socketed tooth removably mounted on the forwardly projecting tang of a supporting body carried by the lip of the bucket, the tooth being removable to permit of resharpening or replacement thereof.

In bucket tooth units of the type described it is desirable that locking means be employed between the tooth and supporting body, which will normally maintain the tooth against loose play and yet permit of ready removal of the tooth for repair or replacement, and it is an object of this invention to provide an improved tooth locking mechanism for this purpose.

Another object of this invention is to provide a locking mechanism for a bucket tooth of the type described, which mechanism is operative to automatically take up any slack occurring between the tooth and supporting body during use of the bucket tooth unit.

A further object of this invention is to provide a locking mechanism, for a bucket tooth unit including a body tank symmetrically and matchingly engaging in a socketed tooth, comprising a boss projecting outwardly from one face of the tang, the corresponding portion of the tooth having a longitudinally elongated slot therethrough and into one end of which slot the boss projects, and a compression spring removably engaging between said boss and the longitudinal inner end of the slot, whereby the spring normally but releasably secures the tooth on the supporting body.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a top plan view, partly broken away, of my improved bucket tooth unit; the locking spring being shown in its initial or unlocked position.

Figure 2 is a similar view but illustrating the locking spring in locked position.

Figure 3 is a longitudinal sectional elevation on line 3—3 of Fig. 2.

Figure 4 is a side elevation of the tooth sup-

porting body and its included outwardly projecting tang.

Referring now more particularly to the characters of reference on the drawing, the numeral 1 indicates the tooth supporting body which is adapted to be mounted on and to project forwardly from the lip of the excavating bucket; the means for attaching said body to the bucket lip being conventional and not here shown. The body 1 tapers forwardly in both a horizontal and vertical plane and at its outer end is formed with a forwardly projecting outwardly tapering tang 2. The upper face 3 of the tang is parallel to but disposed some distance below or offset relative to the plane of the corresponding face 4 of the body 1, whereby to form a shoulder 5. At the sides and bottom the tang is also somewhat offset inwardly relative to the corresponding portions of the body.

10 The removable digging point or tooth comprises a flat plate or tooth 6 of rectangular configuration in plan, which is sharpened at its forward end as at 7.

15 The tooth 6 includes a depending rearwardly opening socket 8 formed to receive the tang 2 therein in matching engagement as shown in Fig. 3; the inner end 9 of the tooth 6 being substantially in abutment with the shoulder 5 when the tang 2 is fully seated in the socket 8. Rigid tongues 10 project rearwardly from the inner end 9 of the tooth 6 adjacent opposite sides thereof and seat in matching sockets 11 formed in the body and opening through the shoulder 5. By reason of the offsetting of the tang surfaces, as described, the tooth and body are substantially flush on all sides.

20 The above described bucket tooth unit is, in its general assembly, a conventional structure and it is to this structure that I apply my novel locking mechanism, and which comprises the following:

25 Intermediate the ends of tang 2 and centrally between the sides of the same, said tang is formed with an integral and upstanding boss 12 which is rectangular in plan.

The tooth 6 intermediate its ends and centrally of the sides thereof is formed with a longitudinally extending, elongated slot 13, which opens into the socket 8. The slot at its forward end has parallel side portions 14 spaced apart a distance only sufficient to receive the rectangular boss 12 therebetween with a relatively close fit. From the parallel side portions 14, the remaining side portions 15 of the slot 13 diverge rearwardly to the rear end 16 of the slot 13, whereby said

rear end is of substantially greater width than the width of the slot between side portions 14. The end 16 of the slot is formed centrally of its ends with a vertical notch 17.

A leaf spring 18, of slightly greater length than the normal distance between slot end 16 and the adjacent side 19 of the boss 12, is disposed edge-wise in the slot and normally engaged in bowed relation with one end seated in notch 17 and the other end abutting said side 19 of the boss and with an adjacent side of the spring in contact with one side of the slot, as at C, whereby to prevent separation of the tooth from the tang, and further to take up any slack which may occur between the tooth and tang during use of the unit. As shown in Fig. 2, the boss 12 is normally disposed a slight distance clear of the forward end of slot 13, which permits the bowed spring 18 to take up any slack and to maintain the tooth firmly engaged on the body tang.

The locking spring 18 is brought into locking position by first disposing the spring in the slot 13 in the somewhat diagonal position shown in Fig. 1; the height of the spring being substantially the thickness of the tooth 6. Thereafter an eccentric tool of any type is engaged between the spring and the closest side of the slot, and manipulated so as to bow the spring and snap it at one end into the notch 17, as shown in Fig. 2. To release the spring the above manipulative steps are reversed, i. e. the eccentric tool is engaged between the concave side of the spring and the adjacent side of the slot, and the tool actuated to snap the spring out of notch 17, whereupon it returns to its initial released position and can be withdrawn from the slot preparatory to separation of the tooth from the tang.

With the above described bucket tooth unit locking mechanism, the tooth is always maintained firmly on the tang as is desirable, and yet with relative ease the operator can remove the tooth for repair or replacement.

While especially designed for use in connection with power shovels or dredges, the present invention is readily adaptable to rooters, scarifiers, and ditching machines.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A releasable locking mechanism for a bucket tooth unit which includes a rearwardly opening socketed tooth engaged on a supporting tang, said mechanism comprising a boss on and projecting outwardly from one face of the tang, the tooth having a slot therein, the slot opening into the socket and the boss projecting into the slot, and a loaded compression spring normally engaged between the rear end of the slot and the adjacent side of the boss.

2. A releasable locking mechanism for a bucket tooth unit which includes a rearwardly opening socketed tooth engaged on a supporting tang, said mechanism comprising a boss on and projecting outwardly from one face of the tang, the tooth having a longitudinally elongated slot

therein, the slot opening into the socket and the boss projecting into the slot, and a loaded compression spring normally engaged between the rear end of the slot and the adjacent side of the boss; the spring being a normally bowed leaf spring disposed edgewise relative to the tang, said rear end of the slot having a notch in which the corresponding end of the spring seats, and the portion of the spring adjacent its opposite end riding the one side wall of the slot adjacent the boss.

3. A locking mechanism as in claim 2 in which the portions of the side walls of the slot adjacent the boss are parallel and receive the boss therebetween with a relatively close fit.

4. A locking mechanism as in claim 2 in which the portions of the side walls of the slot adjacent the boss are parallel and receive the boss therebetween with a relatively close fit; one of said side walls of the slot diverging longitudinally rearwardly from said parallel portion to the rear end of the slot.

5. A releasable locking mechanism for a bucket tooth unit which includes a rearwardly opening socketed tooth engaged on a supporting tang, said mechanism comprising a boss on and projecting outwardly from one face of the tang, the tooth having a longitudinally elongated slot therein, the slot opening into the socket and the boss projecting into the slot, the portions of the side walls of the slot adjacent said boss being parallel and receiving the boss therebetween with a relatively close fit, and a leaf spring disposed on edge in the slot between the rear end of the latter and the boss; the slot increasing in width between the boss and said rear end, the latter having a spring receiving notch therein intermediate the sides of the slot, and the spring normally being bowed with one end seated in the notch and the other end abutting against the boss with an adjacent side portion in contact with one side of the slot adjacent said boss.

6. A releasable locking mechanism for a bucket tooth unit which includes a rearwardly opening socketed tooth engaged on a supporting tang, said mechanism comprising a boss on and projecting outwardly from one face of the tang, the tooth having a longitudinally elongated slot therein, the slot opening into the socket and the boss projecting into the slot, the portions of the side walls of the slot adjacent said boss being parallel and receiving the boss therebetween with a relatively close fit, and a leaf spring disposed on edge in the slot between the rear end of the latter and the boss; the sides of the slot diverging symmetrically rearwardly from said parallel portions of the latter, the rear end of the slot having a spring receiving notch therein intermediate the sides of the slot, and the spring normally being bowed with one end seated in the notch and the other end abutting against the boss with an adjacent side portion in contact with one side of the slot adjacent said boss.

7. A releasable locking mechanism for a bucket tooth unit which includes a rearwardly opening socketed tooth engaged on a supporting tang, said mechanism comprising a boss on and projecting outwardly from one face of the tang, the tooth having a longitudinally elongated slot therein, the slot opening into the socket and the boss projecting into the slot, and a loaded compression spring normally engaged between the rear end of the slot and the adjacent side of the boss; the opposite side of the boss normally being

in clearance relation to the forward end of the slot.

8. A releasable locking mechanism for a bucket tooth unit which includes a rearwardly opening socketed tooth engaged on a supporting tang, said mechanism comprising a boss on and projecting outwardly from one face of the tang, the tooth having a longitudinally elongated slot

therein, the slot opening into the socket and the boss projecting into the slot, and a loaded compression spring normally engaged between the rear end of the slot and the adjacent side of the boss; said spring being of leaf type and normally bowed.

MARSHALL J. WHITE.
